UNITED STATES PATENT OFFICE.

ALEC J. GERRARD, OF CHICAGO, ILLINOIS.

BUNDLING-MACHINE.

1,380,791.

Specification of Letters Patent. Patented June 7, 1921.

Continuation of application Serial No. 287,487, filed April 4, 1919. This application filed November 26, 1920. Serial No. 426,500.

To all whom it may concern:

Be it known that I, ALEC J. GERRARD, a subject of the King of Great Britain, residing at Chicago, in the county of Cook and State of Illinois, have invented certain new and useful Improvements in Bundling-Machines; and I do hereby declare the following to be a full, clear, and exact description of the invention, such as will enable others skilled in the art to which it appertains to make and use the same.

This invention relates to wire twisting machines and has for its object to improve the machine illustrated in the U. S. Patent #1300166, dated April 8, 1919, and issued to Edward Hatch.

With these and other objects in view the invention consists in the novel details of construction and combinations of parts more fully hereinafter disclosed and particularly pointed out in the claims.

This application is a continuation of my copending application #287487, filed April 4, 1919, allowed August 10, 1920, and entitled Bundling machine.

Referring to the accompanying drawings forming a part of this specification, in which like numerals designate like parts in all the views:—

30 Figure 1 is a perspective view of the head of the machine illustrated in said Hatch patent above mentioned;

Fig. 2 is a view similar to Fig. 1, partially broken away and illustrating the opposite side of the said head;

Fig. 3 is a front elevational view of the parts shown in Fig. 1;

Fig. 4 is a sectional view taken approximately on the line 4—4 of Fig. 2;

40 Fig. 5 is a view illustrating the wire twisting gear train;

Fig. 6 is a perspective view of the wire twisting pinion detached;

Fig. 7 is a perspective view of one of the 45 slidable wire holding members;

Fig. 8 is a detail sectional view illustrating the operation of the parts shown in Fig. 7; and

50 Fig. 9 is a plan view of the organized machine as illustrated in the said Hatch patent.

Referring first to Fig. 9, 1 indicates any suitable supporting framework, 2 a reel for holding the wire supported on said frame-

work, 4 the wire twisting head illustrated in Figs. 1, 2 and 3, 5 a pillar rising from the framework 1 for supporting the head 4, 6 a flange on the pillar 5 provided with bolts adapted to enter the holes 7 in the head shown in Fig. 1 for the purpose of securing said head to said pillar 5, 8 a wire tensioning lever pivoted at 9 to the pillar 5 and traversing an arc-shaped member 10 secured to said pillar 5 and to the framework as illustrated.

11 indicates suitable gripping means carried by the lever 8 adapted to seize a bight of the wire 12 when passed therethrough and to tension said wire when the lever is operated all as is explained in the said Hatch patent above mentioned.

13 illustrates the foot lever for operating the machine to raise and lower the supporting means 14 carrying the material to be wired or banded all as will be likewise clear from said Hatch patent.

This invention, as stated above, constitutes an improvement on the said Hatch patent and is particularly directed to the construction of the wire twisting head so that the foregoing parts in themselves constitute no part of this invention.

Referring more particularly to Figs. 1, 2 and 3, the head 4 is composed of the side plates 15 and 16 closed at one end by the member 17, and closed at their top by the cover plate 18, so as to form a hollow space in which is located the wire twisting gear train consisting of a segment 19 provided with a hub 20 keyed on the shaft 21 operated by the lever 22, all as will be clear from Figs. 1, 2 and 5. The said segment 19 meshes with the intermediate gear 23, meshing with the wire twisting pinion 24, provided with the wire receiving slot 25, and with the journaled or pivoted portions 26 adapted to find a bearing in the framework of the machine. Said pinion 24 as is usual in such cases is provided with an enlarged slotted portion 28 adapted to permit two bights of wire to rotate therein, and with the narrower portion 25 only wide enough to receive the two bights 30 and 31 of the wire in parallel relation as is best illustrated in Fig. 5. The enlarged spaces 28 of the slotted pinion 24 are continued through the cut away portion 27 of the frame or head 4 of

65

105

the machine as best shown in Figs. 1, 2, 3, and 5 and are terminated by the relatively narrow slots 32 and 33 with which the slid-
able members 34 and 35 are provided.
5 These said slots 32 and 33 are preferably formed by inserting in the ends of the mem-
bers 34 and 35 the removable hardened steel pieces 36, and the slots 32 and 33 are only sufficiently wide to receive in parallel rela-
10 tion the two bights of the wire 30 and 31 as is the case with the wire twisting pin-
ion 24.

It thus results that as the said slots 32 and 33 will not permit the bights 30 and 31
15 to rotate while the pinion 24 compels them to rotate around the center of said pinion, should the pinion 24 be rotated the said bights 30 and 31 will be twisted together
20 into a firmly holding knot all as is well known.

Attached to the plate 15 of the head 4 is the bracket like member 40 hollowed out as shown, to receive the slidable member 35 and provided with the perpendicularly ex-
25 tending lug or foot 41 having the flat surface 42 forming a continuation of the flat surface 43 of the head 4. On the opposite plate 16 of the head 4 is a similar bracket like member 45 hollowed out to receive the
30 slidable wire holding member 34 provided with a similar perpendicularly extending foot or lug 46 whose flat surface 47 likewise constitutes an extension of the flat surface 43 of the head of the machine. Each of the
35 slidable members 34 and 35 are provided with compressible springs 48 adapted to maintain their forward slotted ends in register with the slots 25 and 28, and they are provided with the adjustable screws or lugs
40 49 and 50 as shown.

Secured to one end of the main driving shaft 21 is an arm provided with a toe 52 adapted to strike the screw 49 of the slidable member 34 and to retract it against the
45 compression of its spring 48 immediately after the wire twisting operation has been completed as will presently appear. Likewise secured to the lever 22 near the other end of the shaft 21 is a similar arm
50 53 provided with a toe 54 adapted to strike the lug or screw 50 with which the slidable member 35 is provided, all as will be clear from Figs. 1 and 2.

Rigid with the bracket 40 is an enlarge-
55 ment 55 on which is mounted the lug 56 carrying the adjustable stop 57 adapted to limit the forward stroke of the lever 22, and mounted on the cover plate 18 is the lug 58 carrying the adjustable stop 59 adapted
60 to limit the backward stroke of the lever 22. A spring indicated at 60 normally main-
tains the lever 22 against its stop 59 as illustrated in Fig. 1.

Pivoted to the lug 55, as at 61 is a cutter
65 52 provided with the rearwardly extending

lever portion 63 provided with a pin, as at 64, to which one end of a spring 65 is attached, the other end of which is attached to the lug 56 as by the pin 67, as best shown in Fig. 1.

70

This said spring 65 maintains the cutter 62 normally in its inoperative position as illustrated while the turning of the lever 22 and the shaft 21 rotates the cam or operating member 69 which contacts with the said lever 63 and thus operates the cutter after the twisting operation, as will be presently disclosed.

75

The bracket member 45, as best shown in Figs. 2 and 4 is provided with an enlargement 70 having a hollow space 71 in which is located a pivoted lever 72 provided with a tooth or detent adapted to take into a notch of the wire holding dog 74 as best illustrated in Fig. 4. Said wire holding dog 74, as
80 will be clear from Figs. 1, 2 and 3, is pivoted to the enlargement 70 as at 75, and is provided with wire holding teeth 76 adapted to grip an end 77 of the wire between themselves and the anvil member 78 with which the lug 46 is provided, all as will be clear from Fig. 3.

85

A plunger member 79 controlled by the spring 80 normally presses the dog 74 against the end 77 of the bight 30 of the wire, as will be readily understood. On the other hand, when said dog 74 is moved out of engagement with the wire, as by pressing upon the handle or lug 81, the tooth 73 of the lever 72 engages said dog 74, as best
95 illustrated in Fig. 4, and holds the said dog in its inoperative position until released by pressing upon said lever 72 as will be readily understood.

100

The operation of this machine is as fol-
lows:—An end 77 is brought beneath the dog 74 by unwinding the wire 12 from the reel 2, and said end 77 is firmly clamped between the teeth 76 of said dog and the anvil 78 whereupon the bight 30 of said wire is
110 first passed through the narrow slot 32, the wider slot 28, the narrow slot 25 and the wider slot 28, the narrow slot 33, and in a clockwise direction, as seen in Fig. 3, around the bundle or package to be wired, where-
115 upon said wire is brought back to the dog 74, past the same, and its bight 31 is brought into the slot 32 so that it will become parallel to the bight 30. Said bight 31 is carried on in a parallel relation to the bight 30
120 through the succeeding slots 28, 25, 28, 33 and then through or between the dogs 11 carried by the lever 8 illustrated in Fig. 9. The foot lever 13 having been operated in the manner disclosed in the said Hatch pat-
125 ent, above mentioned, to compress the bundle, the tensioning lever 8 may now be operated to cause the dogs 11 to put any desired tension on the bight 31 of the wire. It should be observed that, as is best illus-
130

trated in Fig. 9, the dogs 11 are spaced out of line with the slots 32 and 33 or somewhat to the rear of the same so that when the lever 8 is operated the tendency will be to 5 press the bight 31 in against the bight 30, see Fig. 5, so that the said two bights will be maintained firmly in their parallel relation rather than displaced from such a relation. In other words, unless the bights are 10 firmly held in the bottom of the slot 25 during the twisting operation, they are liable to get out of line and to cause the machine to jam. The proper tension having been placed on the wire by operating the lever 8 in the 15 manner described, the hand operated lever 22 is rapidly thrown from its dotted line position, shown in Fig. 5, to its full line position, against the tension of the spring 60.

This throw of the lever 22 causes a definite angular rotation of the twisting pinion 24 by reason of said lever 22 being accurately stopped at a predetermined point by its contact with the adjustable stop 57. Therefore, it results that not only will a 25 predetermined number of twists be placed in the bights 30 and 31 of the wire 12, but the slot 25 will be stopped in a predetermined angular position depending upon the adjustment of the screw 57. If said screw 30 has been adjusted to the position indicated in the drawings, the angular position in which the slot 25 stops will be in the same horizontal plane as the slots 32 and 33; while if said screw 57 is somewhat lowered 35 in its adjustment the lever 22 will move to a lower position than is indicated in Fig. 5, so that said slot 25 may even be turned to occupy a substantially vertical position.

In addition to thus stopping the lever 22 40 and the slot 25 at a predetermined angular position, the parts are so timed that the lugs 52 and 54 carried by the levers 51 and 53 respectively will engage the adjustable screws or lugs 49 and 50 respectively, carried by the sliding members 34 and 35, with the result that said slideable members 34 and 35 will be forced to the rear against the compression of their springs 48 so that their slots 32 and 33 will disappear inside 50 the brackets 45 and 40, and thus bring the twisted portions of the bights 30 and 31 against the cut away portion of the frame of the machine to the end that said bights will be forcibly ejected from said slots 32 and 33. It thus results, whether the slot 25 55 stops in a horizontal or in a substantially vertical position, owing to the particular adjustment of the screw 57, the twisted bights 30 and 31 will be freed from the slots 32 and 33 before said lever 22 ceases its forward movement.

In the meantime, and just before the ejection of said twisted portions of the wire takes place, the cam 69 contacts with the 60 lever 63 of the cutter 62 and causes said cut-

ter to sever the bight 31, only of the wire. As will be clear from Figs. 1, 3 and 9, the bight 30 of the wire passes down in front of the lug 42 and below the cutter 62, while the bight 31 of the wire leaves the slot 33 at a 70 considerable angle to the said bight 30 and passes above the cutter 62 so that the operation of the cutter 62 does not sever the bight 30.

The lugs or feet 41 and 46 with their 75 smooth bottoms 42 and 47 constitute an efficient means for aiding in putting the package under compression in that they form a wider bearing surface than is afforded by the head shown in said Hatch patent, above 80 mentioned.

As soon as the cutting operation has been completed the spring 65 returns the cutter to its inoperative position shown in Fig. 1, and away from the stationary cutting edge 85 90 there illustrated.

The spring 60 immediately returns the lever 22 as above stated, and the stop 59 insures that the slot 25 is in a proper position to receive another bight of the wire. 90

It will now be clear that if the screw 57 occupies one position, the twisted bights 30 and 31 will be ejected from the holding slots 32 and 33 by the time the twisting slot 25 reaches a horizontal position. On the 95 other hand, another adjustment of said screw 57 will cause said slot 25 to move an additional angular distance after reaching a horizontal plane, and thus will permit the twisted bights to fall out of said slot 25 100 under the action of gravity upon the completion of the stroke of lever 22.

It is obvious that those skilled in the art may vary the details of construction as well as the arrangement of parts without departing from the spirit of the invention, and therefore, I do not wish to be limited to the above disclosure except as may be required by the claims. 105

What I claim is:—

1. In a wire tying machine the combination of a wire twisting pinion provided with a slot adapted to receive parallel bights of wire but too narrow to permit said bights to be twisted together in said slot; a slideable member on each side of said pinion having a slot also adapted to receive said bights and to prevent them from being twisted together; means to actuate said pinion to cause said bights to become twisted together 115 outside said slots; and means to move said slideable members at the end of the twisting operation to forcibly eject therefrom said twisted bights of wire, substantially as described. 120

2. In a wire tying machine the combination of a wire twisting mechanism comprising a slideable wire holding member; and means to so move said member at the end of the twisting operation as to forcibly eject 130

the twisted wire therefrom, substantially as described.

3. In a wire tying machine the combination of a wire twisting means comprising a 5 slidable wire holding member; and connections for automatically ejecting the twisted wire from said member at the end of the twisting operation, substantially as described.

10 4. In a wire tying machine the combination of a wire twisting means comprising a slotted spring controlled movable wire holding member; and connections for automatically and forcibly ejecting the twisted wire 15 from said member at the end of the twisting operation, substantially as described.

5. In a wire tying machine the combination of a wire twisting head having a flat bottom and comprising a gear train and side 20 walls inclosing the same; brackets rigid with said walls provided with projecting feet having flat bottoms forming extensions of said first named bottom; and slotted slidable wire holding members housed in said brackets, substantially as described.

25 6. In a wire tying machine the combination of a wire twisting gear train comprising a pinion provided with a slot; a slidable slotted wire holding member coacting with said slot; an actuating lever and connections 30 for operating said gear train and slidable member; and an adjustable stop to limit the movement of said lever, substantially as described.

35 7. In a wire tying machine the combination of a wire twisting gear train comprising a slotted wire twisting pinion; a pair of slidable wire holding members coacting with said pinion; means to hold in position 40 a wire encircling a package; means to tension said wire; means to actuate said gear train to twist together two bights of the tensioned wire; connections with said actuating means for forcibly ejecting the twisted wire from said holding members; and means to limit the throw of said actuating 45 means, substantially as described.

50 8. In a wire tying machine the combination of a wire twisting gear train comprising a slotted wire twisting pinion; a pair of slidable slotted wire holding members coacting with said pinion; means comprising a dog to hold in position a wire encircling a package; means comprising a lever to tension 55 said wire; means comprising a lever to actuate said gear train to twist together two bights of the tensioned wire; connections comprising levers with said actuating means for forcibly ejecting the twisted wire from said holding members; and adjustable means to limit the throw of said actuating means, substantially as described.

60 9. In a wire tying mechanism, means for

gripping the free end of a wire; means for severing the wire subsequent to the training 65 of the same about a bundle of material; slidable wire holding means arranged between the wire gripping means and the cutting means; and wire twisting means located intermediate the slidable wire holding 70 means, substantially as described.

10. In a wire tying mechanism, means for gripping the free end of a wire; means for severing the wire subsequent to the training 75 of the same about a bundle of material; slidable wire holding means arranged between the wire gripping means and the cutting means; wire twisting means located intermediate the slidable wire holding means; and means for operating synchronously the 80 slidable wire holding means and the wire twisting means, substantially as described.

11. In a wire twisting and tying mechanism means for gripping the free end of a wire; means for severing the wire subsequent 85 to the training of the same about a bundle of material; slidable wire holding means arranged between the wire gripping means and the cutting means; wire twisting means located between the slidable wire holding 90 means; means for operating synchronously the slidable wire holding means and the wire twisting means; and yielding means for opposing the sliding movements of the wire holding means, substantially as de- 95 scribed.

12. The combination of a rotatable wire twisting pinion of slotted slidable wire holding members arranged on opposite sides of the rotatable wire twisting pinion; a lever 100 for operating the rotatable wire twisting pinion and controlling the wire holding members; and a pair of adjustable stops for said lever, substantially as described.

13. In a wire tying machine the combination of a wire twisting mechanism, comprising a rotating wire twisting slot and a slidable wire holding member; means for forcibly ejecting the twisted wire from said holding member; and means for stopping 105 the rotation of said wire twisting slot after the ejecting operation and after passing a horizontal position, substantially as described.

14. In a wire tying machine the combination of a wire twisting mechanism comprising a rotating wire twisting slot and slidable wire holding members; means for forcibly ejecting the twisted wire from said holding members at the end of the wire twisting 110 operation; and means for automatically stopping the rotation of said wire twisting slot after it passes a horizontal plane, substantially as described.

In testimony whereof I affix my signature. 125
ALEC J. GERRARD.
